ELECTRONIC RELAY

Earle B. McDowell and Pieter Juchter, Scotia,
N. Y., assignors to General Electric Company,
a corporation of New York

Application December 9, 1944, Serial No. 567,513

5 Claims. (Cl. 175—320)

1

Our invention relates to electronic relay circuits, and more particularly to improved time delay relay circuits of this type.

Many electronic time delay circuits have been employed for various industrial applications. It is an object of our invention to provide an improved circuit of this type which is simple, which does not require that the initiating contacts carry substantial current, and which may be employed where the circuit of the initiating contacts includes substantial resistance.

It is another object of our invention to provide an improved time delay circuit having one sequence of energization of the load circuit for each closing and opening of the initiating switch which is readily converted to a different sequence of operation.

It is still another object of our invention to provide a new and improved electronic time delay circuit in which the timing circuit is modified in response to a timing operation.

For a better understanding of our invention, reference may be had to the following description taken in connection with the accompanying drawing, and its scope will be pointed out in the appended claims.

In the drawing, Fig. 1 is a schematic representation of one embodiment of our invention; Fig. 2 is a schematic representation of a modification; and Fig. 3 is a schematic representation of still another modification.

Referring now to the drawing, a load circuit 1, such as the operating coil of an electromagnetic relay 2, is energized from a source of alternating current provided by the secondary winding 3 of a transformer 4 through the anode-cathode circuit of an electric valve 5, which is preferably of the high vacuum type. As illustrated, the valve includes an envelope enclosing an anode 6, a cathode 7 and a control member or grid 8. The primary winding 9 of the transformer 4 is energized from an alternating current circuit 10. A capacitor 11 is preferably connected across the operating coil 1 of the electromagnet to smooth out the energization of the coil. The relay 2 may be provided with contacts to control any desired number of circuits and, as illustrated, includes normally open contacts 12 and normally closed contacts 13 for controlling circuits 14 and 15, respectively.

The conductivity of the electric valve 5 is controlled by the operation of an initiating switch illustrated schematically as a push button 16. It will be readily understood that the initiating switch may be provided by the contacts of any

2

suitable instrument such as a level indicator or thickness gauge, for example. The control member 8 is connected with the cathode 7 through a circuit including a resistor 17, the contacts of the initiating switch 16, a switch 18 and a resistor 19 which provides a source of negative bias for the control member 8. The resistor 19 is connected in parallel with a capacitor 20 and in series with the anode-cathode circuit of an electric valve 21 and a winding 22 on the transformer 4. As will be readily understood, the circuit including winding 22 and valve 21 provides a rectifier circuit for producing a negative bias across resistor 19. The circuit of the control member 8 also includes a capacitor 23 permanently connected between the control grid 8 and the cathode 7. Connected in parallel with capacitor 23 is a resistor 24 and a switch 25. As will be described in detail later, switches 18 and 25 are not normally operated in the operation of the relay but are provided to change the circuit connections to provide a different time delay circuit having a different sequence of energization of the load circuit for each operation of the initiating switch 16.

The operation of the embodiment of our invention described above is as follows: With the transformer 4 energized and the initiating switch 16 open, the control member 8 is maintained at cathode potential by the direct connection of resistor 24 between the cathode and control member. Under these conditions, electric valve 5 conducts current to energize electromagnetic relay 2 and operate contacts 12 and 13. Upon closure of the initiating switch 16 the negative bias of resistor 19 is impressed on the control grid 8 through resistor 17, the circuit being completed through capacitor 23. By making resistor 17 small the control grid assumes a negative potential substantially instantaneously and conduction by electric valve 5 is prevented or reduced to such a low value that control relay 2 is deenergized. Upon opening of the switch 16 the control grid 8 remains sufficiently negative to prevent relay 2 from picking up for an interval determined by the magnitude of resistor 24 which provides a discharge path for capacitor 23. Thus the system of Fig. 1 as described above with resistance 17 and the contact resistance relatively small and resistance 24 relatively large provides for substantially instantaneous deenergization of relay 2 upon closure of contact 16 and for energization of the relay with a time delay after opening of the switch 16.

If switches 18 and 25 are moved upwardly, as

viewed in Fig. 1, to engage contacts 26 and 27, respectively, it will be noted that the negative bias of resistor 19 is permanently connected to the circuit of the control member through resistance 24, and initiating switch 16 is connected in series with resistor 17 and across the control member to the cathode circuit of the electric valve. With this arrangement it will be apparent that the control member 8 is normally maintained at a substantially negative voltage to maintain the relay 2 deenergized. Upon closure of the initiating switch 16, capacitor 23 discharges rapidly through the relatively small resistor 17 to energize the load circuit substantially instantaneously upon closure of the initiating switch. Upon opening of the initiating switch 16, capacitor 23 charges to a negative value through the relatively large resistor 24 to again render the valve 5 nonconducting but with a time delay. Thus the circuit as illustrated in Fig. 1 may be readily converted to a different circuit having a different sequence of energization and deenergization of the relay for each operation of the initiating switch 16.

In some installations it is undesirable or impractical to maintain the resistance 17 in the initiating circuit low. For example, in liquid level control systems the circuit of the probes employed as contact makers may have considerable resistance. While this resistance is desirable in many applications and may serve a useful purpose in limiting current flow through delicate initiating contacts it may operate with the timing capacitor to produce an unwanted delay in the sequence of operation of the control relay. In the arrangement of Fig. 1, for example, if resistor 17 or the contact resistance is of appreciable magnitude there will be a delay in the dropping out of relay 2 upon closure of initiating switch 16, as well as a delay in the energization of relay 2 upon opening of contact 16.

In Fig. 2 of the drawing we have shown a circuit arrangement which is very similar to the circuit of Fig. 1, with an additional set of normally open and normally closed contacts on the relay 2 for controlling the circuit of capacitor 23. In Fig. 2, those parts corresponding to the parts of Fig. 1 have been designated by corresponding reference numerals. In Fig. 2 in addition to the external circuit controlling contacts 14 and 15 the relay 2 is provided with a normally open contact 28 and a normally closed contact 29. The normally open contact 28, when closed, connects the capacitor 23 between the cathode and grid of the electric discharge device 5 in the same manner as it is connected in Fig. 1, and the normally closed contact 29 establishes a shunt circuit across capacitor 23 for discharging the capacitor.

In the operation of the modification shown in Fig. 2, the control member 8 of the electric valve 5 is normally connected with the cathode through resistor 24 so that electric valve 5 is conducting and the coil 4 of relay 2 is energized, contact 28 is closed, and contact 29 is open. This establishes a circuit for capacitor 23 in the grid circuit in parallel with resistor 24. When the initiating switch 16 is closed, the negative voltage appearing across resistor 19 is impressed on the circuit of the control member through resistance 17 which has been used to illustrate the total resistance in the initiating circuit. With the relay 2 energized, the capacitor 23 draws current through the resistor 17 and delays the application of the negative voltage to the control member of valve 5 so that the relay is deenergized with a time

delay. However, when relay 2 drops out, it disconnects the capacitor 23 and establishes a discharge circuit for the capacitor through contact 29 so that upon opening of the initiating circuit the control member of electric valve 5 immediately assumes the potential of the cathode and the relay is picked up immediately.

In Fig. 3 is shown a similar circuit arrangement in which the controlling contacts and capacitor are arranged to drop out the relay immediately upon closing of the initiating switch, and to pick up the relay with a time delay upon opening of the initiating switch. In Fig. 3 the relay has been shown as energized from a direct current supply circuit. Referring now to Fig. 3, the relay is energized from a direct current supply circuit 30 instead of the alternating current supply circuit 10. The anode-cathode voltage for the electric valve and the negative bias for the control member thereof, corresponding to the bias produced across resistor 19 of Fig. 1, is provided by voltage resistors 31 and 32, respectively, which are connected in series across direct current supply circuit 30. Resistor 32 is preferably provided with an adjustable tap 33 for adjusting the magnitude of the bias voltage. In the arrangement of Fig. 3, the contacts in circuit with capacitor 23 have been arranged so that when the relay 2 is energized, the terminal of capacitor 23 remote from the cathode of electric valve 5 is connected to the source of negative bias voltage. As illustrated in the drawing, this is accomplished by a normally open contact 34 of relay 2 and a conductor 35. A normally closed contact 36 of relay 2 is provided for connecting this terminal of the capacitor directly to the control member when the relay 2 is deenergized. With this circuit arrangement, it is apparent that electric valve 5 conducts and relay 2 is energized before initiating contact 16 is closed. Upon closure of the initiating switch 16, the negative voltage is immediately impressed on the control member through the resistor 17 to deenergize the relay immediately. This closes contact 36 and opens contact 34 and places the negatively charged capacitor across the grid-to-cathode circuit. When contact 16 is opened, the voltage of the grid rises at a rate determined by the discharge of capacitor 23 through resistor 24. Thus the delay that might otherwise result from charging capacitor 23 through resistor 17 is eliminated and immediate drop-out of the relay is accomplished upon closure of the initiating switch 16 while energization of the relay upon opening of the initiating switch is accomplished with a time delay.

In the specification and in the appended claims, "permanently connected" is employed to distinguish from circuits which are normally opened and closed during operation of the device and is applied, for example, to the circuit including switch 25 which may be operated to provide a different circuit but which is not intended to be operated during operation of the circuit originally established.

While we have shown and described a particular embodiment of our invention, it will be obvious to those skilled in the art that changes and modifications may be made without departing from our invention in its broader aspects, and we, therefore, aim in the appended claims to cover all such changes and modifications as fall within the true spirit and scope of our invention.

What we claim as new and desire to secure by Letters Patent of the United States is:

1. In combination, a supply circuit, an electromagnetic relay including an operating coil, an electric valve including an anode, a cathode and a control electrode means connecting said supply circuit, the operating coil of said relay and the anode-cathode circuit of said valve in series, a resistor connected between said cathode and control electrode, a capacitor, a source of direct voltage, electrical connections from said source for supplying a charge to said capacitor, a circuit controlled by said relay for connecting said capacitor in parallel with said source of direct voltage when said relay is in one operative position to provide a charge on said capacitor for supplying a negative bias voltage to said control electrode and for establishing a discharge circuit for said capacitor when said relay is in a second operative position, and a circuit including resistance and a normally open initiating contact connecting said direct voltage between said control electrode and said cathode with the negative terminal of said source electrically nearer said control electrode.

2. In combination, a supply circuit, an electromagnetic relay including an operating coil, an electric valve including an anode, a cathode and a control electrode means connecting said supply circuit, the operating coil of said relay and the anode-cathode circuit of said valve in series, a resistor connected between said cathode and control electrode, a capacitor, a source of direct voltage, electrical connections from said source for supplying a charge to said capacitor, a circuit controlled by said relay for connecting said capacitor in parallel with said source of direct voltage when said relay is in one operative position to provide a charge on said capacitor for supplying a negative bias to said control electrode and for disconnecting said capacitor when said relay is in a second operative position, and a circuit including a resistance and a normally open initiating contact connecting said direct voltage between said control electrode and said cathode with the negative terminal of said source electrically nearer said control electrode.

3. In combination, a supply circuit, an electromagnetic relay including an operating coil, an electric valve including an anode, a cathode and a control electrode means connecting said supply circuit, the operating coil of said relay and the anode-cathode circuit of said valve in series, a resistor connected between said cathode and said control electrode, a capacitor, a source of direct voltage, electrical connections from said source for charging said capacitor, a circuit controlled by said relay for connecting said capacitor in parallel with said source in one operative position of said relay and in parallel with said resistor to supply a negative bias voltage to said control electrode only when said relay is in a second op-

erative position, and a circuit including an initiating contact connecting said direct voltage between said control electrode and said cathode.

4. In combination, a supply circuit, a relay, including an operating coil, an electric valve including an anode, a cathode and a control electrode, means permanently connecting said supply circuit, the coil of said relay and the anode-cathode circuit of said valve in series, a resistor connected in the control member-to-cathode circuit of said electric valve, a capacitor, a source of direct voltage, means including connections from said source to said capacitor established in a first operative position of said relay for precharging said capacitor to a predetermined voltage, an initiating switch for controlling the voltage on said control electrode to effect operation of said relay to a second operative position, and means responsive to the operation of said relay to said second operative position for connecting said precharged capacitor in circuit with said control electrode to impress a transient negative bias voltage thereon determined by said capacitor and said resistor.

5. In combination, a supply circuit, a relay, an electric valve including an anode, a cathode and a control electrode, means connecting said supply circuit, said relay and the anode-cathode circuit of said valve in series, a resistor connected in the control member-to-cathode circuit of said electric valve, a capacitor, a source of direct voltage, means including connections from said source to said capacitor established in a first operative position of said relay for precharging said capacitor to a predetermined voltage, an initiating switch for controlling the voltage on said control electrode to effect operation of said relay to a second operative position, and means responsive to the operation of said relay to said second operative position for connecting said precharged capacitor in circuit with said control electrode to impress a transient negative bias voltage thereon determined by said capacitor and said resistor.
